Primary Examiner — Darcey E Gottschalk(74) *Attorney, Agent, or Firm* — Maier & Maier, PLLC(57) **CLAIM**

The ornamental design for an arm brace, as shown and described.

DESCRIPTION

FIG. 1 is a top-rear-left isometric view of an arm brace, showing my design;

FIG. 2 is a top plan view thereof;

FIG. 3 is a bottom plan view;

FIG. 4 is a front side view of the arm brace shown in an unfolded configuration for clarity of disclosure;

FIG. 5 is a rear view thereof;

FIG. 6 is a top view thereof;

FIG. 7 is a bottom view thereof;

FIG. 8 is a right view thereof; and,

FIG. 9 is a left view thereof.

The broken line showing in the Figures shows portions of the arm brace and forms no part of the claimed design.
